Primary Examiner—Alan P. Douglas*Assistant Examiner*—Robin V. Taylor*Attorney, Agent, or Firm*—Norman Friedland**[57] CLAIM**

The ornamental design for a multiple orifice nozzle sprinkler, as shown and described.

DESCRIPTION

FIG. 1 is a front perspective view of a multiple orifice nozzle sprinkler showing my new design;

FIG. 2 is a partial view of the invention illustrating the front elevation view thereof;

FIG. 3 is a side elevation view thereof showing the opposite side to FIG. 2; and,

FIG. 4 is a top plan view thereof.

The sprinkler is shown broken away in FIGS. 2 and 3 to indicate indeterminate length.

The broken line showing of environment and indicia is for illustrative purposes only and forms no part of the claimed design.
